UNITED STATES PATENT OFFICE.

ALFRED H. SMITH, OF CHAPPAQUA, NEW YORK; MAUDE EMERY SMITH AND EMERY HOLLAND SMITH, EXECUTORS OF THE ESTATE OF SAID ALFRED HOLLAND SMITH, DECEASED, ASSIGNEES TO THE LESS CARLOAD LOTS COMPANY, OF WILMINGTON, DELAWARE, A CORPORATION OF DELAWARE.

FREIGHT CARRIER.

Application filed December 21, 1921. Serial No. 524,030.

To all whom it may concern:

Be it known that I, ALFRED H. SMITH, a citizen of the United States, and residing at Chappaqua, in the county of Westchester 5 and State of New York, have invented certain new and useful Improvements in Freight Carriers, of which the following is a specification.

The practice of shipping less than carload lots of freight in containers, which containers are designed in their connection with the carrier, to be removed at different stations along the route, has given rise to the necessity of providing some means to 10 transport these containers to the consignee, and at the same time preserve the security 15 of the goods in the containers while they are transported from the railroad station to the place of the business of the consignee. 20 This is especially important in cases of mail, as has been demonstrated recently by very heavy robberies of the United States mail in some of our large cities.

The object of my invention is to provide 25 a carrier, a motor truck or a trailer, to transport these containers between the point of destination and the railroad station, and maintain the security of the goods in the containers while being thus transported, the 30 same as when the containers are on the railroad carriers.

My invention consists of a carrier designed to be propelled or drawn along the 35 streets of a city or wagon roads, such a carrier being provided with bulkheads between which the containers are securely and safely positioned so that the doors cannot be opened until the bulkheads are lowered.

My invention consists of the combination 40 with a motor truck having a platform with bulkheads extending vertically from the platform, containers positioned on said platform and provided with a door which door is immediately back of one of said bulkheads when the container is loaded on the truck, whereby the door cannot be opened until the bulkhead is lowered or the container raised above the top edge of the bulkhead.

50 In the drawings:

Figure 1 is a side elevation of a truck embodying my invention,

Fig. 2 is an enlarged detail rear elevation of Figure 1, parts being broken away,

Fig. 3 is a large detail plan view of one 55 corner of the truck and container, and

Fig. 4 is a large detail elevation at one corner of the truck and container.

The reference numeral 1 designates the truck, or the suitable carrier, designed to be 60 moved along city streets or roads and provided with a platform 2, upon which platform are disposed vertical side and end bulkheads 3 and 4, respectively, which project a substantial distance above the platform 65 2.

The containers 5 are adapted to be loaded on the platform between the bulkheads 3 and 4, with the lower portion of the door 6 of the container below the top edge of 70 the bulkheads as shown by dotted lines in Fig. 2.

The bulkheads are provided with suitable guide-ways 7 shown by dotted lines in Fig. 2, while the containers are provided with 75 guides 8, also shown by dotted lines in Figure 2, adapted to enter the guide ways 7 as the containers are loaded between the bulkheads. The bulkheads 4 are provided with slots 9 near each end thereof, through 80 which project the arm 10, which is secured to the container, said arm 10 being adapted to be engaged by a latch 11, which is mounted on the reciprocating rod 12, which rod is in turn pivotally fastened at its lower end to 85 the short arm 13 of the bell crank lever 14, which lever is pivotally mounted at 15 to a suitable casting 16 mounted on the platform 2, so that the rod 12 is adapted to be swung on its pivot to bring the latch 11 vertically 90 over the arm 10, whereby the bell crank lever 14 is moved upon its pivot bringing the latch into engagement with the arm 10 as clearly shown in Fig. 4.

The containers are provided with suitable braces 17 and with lifting ears 18. It will be seen that when the containers are in position on the truck shown in Figures 1 and 2, it is impossible to open the door 6 to gain access to the contents of the container without first elevating the containers above the bulkheads 3 and 4, and as it is impossible to do this without the aid of a crane, it will be seen that theft of the container while in transit through streets is 105 impossible.

While I have selected the construction shown in the drawings for the purpose of il-

lustrating my inventive thought, it will, of course, be understood that my invention is not limited to such construction as changes may be made within the scope of the appended claim.

What I claim is:

The combination with a motor truck having a platform, bulkheads extending vertically from the platform, vertical slots in some of said bulkheads opening at the top of such bulkhead, guideways secured to some of the bulkheads, of a container on said plat-

form and provided with a door disposed immediately back of one of said bulkheads whereby the door cannot be opened while the container is on the truck, guides on the container constructed to interlock with said guideways, arms on the container projecting through said slots, and means to lock said arms in said slots.

In testimony whereof I affix my signature.

ALFRED H. SMITH.
